UNITED STATES PATENT OFFICE.

JOHN RIISE, OF DOYLESTOWN, OHIO.

DESIGN FOR A MOTOR-VEHICLE RADIATOR.

Application filed May 29, 1924. Serial No. 9,738. Term of patent 14 years.

To all whom it may concern:

Be it known that I, JOHN RIISE, a citizen of the United States, residing at Doylestown, in the county of Wayne and State of Ohio, have invented a new, original, and ornamental Design for Motor-Vehicle Radiators, of which the following is a specification, reference being had to the accompanying drawing, forming a part thereof.

Figure 1 is a front elevation of the radiator; and

Figure 2 is a side elevation thereof.

I claim:

The ornamental design for a motor vehicle radiator, as shown.

JOHN RIISE.
